DESIGN FOR A CHILD'S TRAINER OR SIMILAR ARTICLE

Phil Skolnik, Chicago, Ill.

Application December 1, 1944, Serial No. 116,664

Term of patent 14 years

(Cl. D15—8)

To all whom it may concern:

Be it known that I, Phil Skolnik, a citizen of the United States and a resident of the city of Chicago, in the county of Cook and State of Illinois, have invented a new, original, and ornamental Design for Child's Trainer or Similar Article, of which the following is a specification, reference being had to the accompanying drawing, forming part thereof.

Fig. 1 is a perspective view of the child's trainer showing my new design, such view being of the right hand front corner thereof;

Fig. 2 is another perspective view of the child's trainer as viewed from the left hand rear corner thereof; and

Fig. 3 is a plan view of the same.

I claim:

The ornamental design for a child's trainer or similar article, substantially as shown.

PHIL SKOLNIK.
